4 Claims. (Cl. 25—131)

1

This invention relates to sliding moulds for the moulding of concrete walls and the like, provided with a working platform and possibly a lattice-work.

In sliding moulds of the above type used up to now the working platform, and the lattice, if any is provided, is rigidly connected with the mould proper. In practice this has proved to involve certain inconveniences. As a matter of fact, when the sliding mould is being raised, especially if performed manually by the use of screw-jacks, it is impossible to provide for exactly equal lifting at all points. If, on the other hand, hydraulic or pneumatic lifters are used, it is certainly possible, by adapting the height of lifting to a minimum to control the inclination to the vertical of the platform which will occur as a consequence, but even a very small inclination involves substantial frictional forces between the wall-moulds and the concrete wall, and simultaneously forces produced by the horizontal, angularity acting on the wall subject the freshly poured concrete to a greater stress than it can usually resist.

The invention, the purpose of which is to provide a more rapid process of moulding by using sliding moulds, involving a minimum of stresses upon the fresh concrete, still remaining within the height of the mould or immediately below the same, is chiefly characterized by the fact that the walls of the moulds are made up of a number of rigid elements, which, in relation to each other, at least to a certain extent, are movably or resiliently connected to each other and that the connections between the linings of the mould and the working platforms and the brace work, respectively, are yielding.

The invention will be more fully explained hereinafter with reference to a number of embodiments of the same diagrammatically shown in the attached drawing and in connection therewith further characteristic features of the invention will be set forth.

In the drawing, Fig. 1 is a vertical section of a practical embodiment of the sliding mould device according to this invention. Fig. 2 is a plan view of Fig. 1. Fig. 3 is an enlarged view of a detail of Fig. 1. Fig. 4 is an enlarged view of a detail of Fig. 1. Fig. 5 is a diagrammatic reduced plan view of Fig. 1. Fig. 6 is a diagrammatic plan view of a modified supporting device for the sliding mould. Fig. 7 shows a detail of Fig. 6. Fig. 8 shows a modified mould lining. Fig. 9 shows a yoke construction according to the invention. Figs. 10 and 11 both show a hori-

2

zontal section of the yoke of Fig. 9 taken on the line X—X and XI—XI, respectively.

Fig. 12 is a plan view of a building of rectangular cross section in course of being moulded by the use of a sliding mould. Fig. 13 is a vertical section of a wall of the building according to Fig. 12 surrounded by a sliding mould. Fig. 14 is a horizontal section of a corner of the same building together with surrounding parts of the sliding mould device. Fig. 15 is a vertical section taken adjacent to a corner of the building.

When pouring into moulds of the previously known rigid type, care must be taken that the lifting occurs substantially concentrically, that is, that there will be no or only negligible inclination to the vertical of the mould (and of the entire arrangement) during the lifting process, since otherwise horizontal stresses on the still unsettled concrete wall will arise, especially in a horizontal cross section of the concrete wall, at the level of the lower edge of the mould. With relatively great inclination of the entire mould assembly, said stresses may become so heavy that breaks will occur in the concrete wall and a poured ring be included in the lifting movement of the mould.

This difficulty is eliminated in accordance with the present invention.

A practical embodiment of the invention is illustrated in Figs. 1 and 2, wherein numeral 9 designates an outer wall of a mold comprising a number of sections, connected together at the top. Numeral 10 designates an inner wall which also comprises rigid, independently movable sections. The mould sections of both walls have in common that they are peripherally held together at the top. The walls of the moulds are held together by means of a number of yokes 11 arranged around the periphery, which yokes serve, partly, to maintain the distance between the mould walls 9 and 10 in diametrical direction, and for carrying the mould.

Fig. 1 further illustrates a stage in moulding a concrete wall for a silo 12, the yokes 11, and thereby the mould 9, 10 being lifted by a number 45 of hydraulic, so called climb fasteners 13, climbing on climb irons 14 arranged in the concrete wall 12. For the purpose of stiffening the climb iron 14, a stiffening pipe 15 extends from the top of the yoke or from the climb fastener 13 proper down into the concrete. The length of said pipe may vary in many ways and if one, for example, allows the same to reach the bottom of the mould, one avoids the bending-out of the climb iron thus preventing it from exerting any stresses on the 55 freshly poured concrete, still in the mould, and

making it possible to recapture the climb iron 14 after the moulding has been finished, because said climb iron has, for reasons easily understood, not become solidly embedded in the concrete 12.

A working platform 16 belonging to the moulding apparatus is by means of a number of claw-like bent-over forks 17, hingedly connected to yokes 11, each supporting a climb fastener. The manner in which said joint is constructed, is more clearly shown in Fig. 3, wherein 18 designates a bearing pin protruding on both sides of a yoke 11, said pin serving as a support and bearing for a fork 17, the claw-shaped part of which clasps the pin from above. This connection is shaped in such a way, as to permit turning movements as well as displacing movements between yoke and platform if the platform should diverge from its horizontal position. In order to provide for a distribution of the lifting forces even to such zones of the mould periphery, there are no climb fasteners. In accordance with Figs. 1 and 2, a number of fork members 19 are provided, which contrary to previously mentioned members 17 have the claw-enclosed cavity turned upwardly, but otherwise the same relative movements may be permitted, like the fork 17. An enlarged view of the fork 19 which engages the bearing pin from below is shown in Fig. 4.

The apparatus is also provided with an upright 20 fixed in the center of the platform and at the lower end of said upright, a number of rods 21 are, with one of their ends, fixed so as to form a framework together with said platform.

The other ends of said rods are fastened to the fork-members 17 and 19. As shown in Figs. 1 and 2 there are three hydraulic lifters 13 placed at equal distances apart around the periphery of the mould, that is with a displacement of 120°. The entire sliding mould equipment and workers on the platform 16 are lifted by the three lifters 13, said lifters through the respective framework 16, 21, effect a lifting force on the upright 20.

In performing a rapid and safe slide moulding process without disturbing the freshly poured concrete it is advantageous to arrange three main carrying points for the mould and platform. However in lifting a wall mould it is most desirable to have more carrying points than three. For this reason the framework system converges to an upright 20. Thus, the three primary lifting points are, through the system in question, able to transfer and distribute lifting forces to as many points at the periphery as may be desirable.

As apparent from Fig. 1, all hinge-points or bearing pins 18 are positioned, as seen in a plan view, between the inner and outer walls of the mould. Conforming to Figs. 5 and 9 the platform 16, lattice work 21 and walls 9-10 are arranged in such a way in relation to each other that an imagined elongation of the beams 16 of the platform and further of the struts 21 of the lattice work intersect one another on the vertical line through the hinged connection to the mould.

The plane in which the lifting forces are primarily distributed between two lifting points or hinged points 8 are represented by the line 23 in the plan of the sliding mould arrangement according to Figs. 1 and 2 shown in Fig. 5 on smaller scale. The mould sections will thereby be caused to have a tendency to become oblique through the effect of gravity, since the vertical plane through the turning axis 23 is located within the center plane of gravity of the section. Mostly, especially in very light mould sections or

in low moulds this has no importance. Yet in other cases when it is of more importance that the planes of turning, gravity points and sliding frictions should coincide or at least approximate one another, the hinged points 8 according to the invention may be displaced outside the outerlining of the mould as diagrammatically shown in Fig. 6, whereby the planes will, instead, co-incide with that designated by 24 in the figure. The suspension is more clearly depicted in Fig. 7.

When moulding relatively thin concrete walls the climb irons when deflected and further the encasing, stiffening pipe, when in positions inclined to the vertical, weaken the wall to a considerable degree simultaneously as the cross section of the wall decreases. For such reason one may, according to the invention, provide for instance the outer lining with bulges, designated by 25 in Fig. 8, whereby the mould will produce a wall having a number of external vertical concrete cords. It may be true that such cords are not from a point of beauty, to be preferred, but they will give the wall an increased resistance against the actuation of external forces, such as wind etc. during its construction as well as its final use.

Moulds of the last mentioned type will, for reasons easily appreciated, be eccentrically acted upon relative to the center of gravity, while a corresponding eccentric actuation in the opposite direction is obtained within the middle portion of the mould section. The moments of the frictional forces acting upon the entire mould section may thus, replacing the lifting points outwardly in accordance with Fig. 7, be brought to equally distribute themselves around the line of connection between the lifting points.

Another detail which in a preferable manner contributes to the stiffness of the system is found in the shaping of the yoke 11, as shown in Fig. 9, which yokes having only one bridge member, (made up of two riveted plates 26) may be made low (that is, their topmost edges do not extend far above the platform) and in any case present sufficient stiffness. The lifter 13 is then placed above the bridge member.

In the arrangement shown in Figs. 9-11 a yoke 11 is fixed to one of the ends of a rigid mould section, according to the invention, said yoke being made up of two vertical yoke legs from angle iron, extending within the section and somewhat above same. Fixed to the topmost part of each yoke leg is an angle iron 27, of the same dimension, by means of seam welding, making the cross section of each such yoke leg quadrant at the top part in accordance with Fig. 10. The cross section of the base part of the same leg is apparent in Fig. 11. Through this arrangement the yokes will be as close to the moulded product as possible, which means that the eccentricity of the lifting force transferred will attain a minimum. In other respects the arrangements will be very simple and inexpensive, will lend itself to simple assembly and disassembly and will facilitate considerably the distribution of concrete from the platform since the yoke in this manner will not encroach on the space for a turnable hopper for the distribution of the concrete, placed on the platform, said hopper being hereinafter described.

Such a hopper 28 is shown in Figs. 1-2 and comprises a basket, movable on wheels. Two radially extending rods 30 turnable around the middle upright 20 serve as shafts for the hopper. When distributing concrete to the mould the concrete is hoisted off the ground in a vessel 31 by means

of a hoist whereafter the vessel is swung over the hopper 28 and emptied in same by the opening of a lid 33 at the bottom of the vessel. From the hopper the concrete is in turn distributed to the different parts of the mould by successive turning of the hopper 28 on the working platform. It may be noted that it might in certain cases be preferable to let the outer lining 9 of the mould rise higher than the inner one, thus forming a screen, preventing the concrete from being thrown outside the linings of the moulds when transferring concrete from the hopper 28 to the mould.

The apparatus according to the invention purported to eliminate the angularity of a wall mould due to unequal lifting at lifting points in different walls, may also be applied to slide moulding of, for example dwelling houses. The wall mould is then shaped as panels and the lateral pressures acting upon same are taken up by a number of yokes of which certain are provided with lifters. Assuming that the working platform during the lifting operation becomes oblique said condition will not involve angularity or the introduction of undesired horizontal strains upon the wall moulds. The internal corners are shaped so that vertical forces may be transferred from one side wall to another, without the moulds in question being mutually rigidly connected in horizontal direction. The movement of one mould in this case will not give such a fastening to the adjacent mould wall, that additional loads will be imposed upon the fresh coured concrete.

A sliding mould for the moulding of dwelling houses and the like is shown in Figs. 12-15, in which 34 designates an outer mould, made up of a number of plane sheets of plate. Further, 35 designates an inner mould, built up in the same way. Both moulds are sustained in a plurality of points by yokes 36, of a shape shown in Fig. 13, some of the yokes being provided with climb fasteners in a manner previously described in connection with annular concrete moulds. These climb fasteners may preferably be positioned at equal distances apart around the mould. Protruding from the legs of the yokes 36 are triangular brackets 37 welded thereto, said brackets carrying beams which in turn carry a plurality of cross beams 39. These latter form a support for a working platform 40 made of iron plate or boards.

In order that the sliding mould in oblique position will not impair the concrete column being in course of moulding, the corner connections are made yielding as is apparent from Figs. 14 and 15. The iron sheets forming the mould, are stiffened by angle irons 41 and 42 respectively in vertical as well as in horizontal direction, two such angle irons 41 at the corners of the outer lining of the mould being only joined by a bolt 43, while depending essentially freely adjacent each other. A similar arrangement is also provided at the corners of the innerlining of the mould. As more clearly appears from the vertical cross section shown in Fig. 15 a rectangular plate is fixed by welding to the topmost part of the angle irons of one of the walls of the mould, said plate by means of a bolt 45 fixing one side of the mould to that placed at right angles thereto. For the rest both walls of the mould depend essentially freely, though relatively adjacent each other.

With possible oblique condition of the working platform, caused by unequal lifting at different points the inner and outer linings of the mould may permanently maintain their vertical posi-

tions, without subjecting the mass of concrete to horizontal shearing forces at the lower part. This may be attained since the corner connections between the linings of the mould are yielding and since the beams resting loosely on each other in such an obliquity are able freely to assume such positions, that moments of power affecting the concrete thereby are avoided.

We claim:

1. A concrete casting apparatus, comprising inner and outer walls forming a sliding mould, said walls being connected and spaced apart by a plurality of yokes for lifting the mould, lifters rigidly connected with some of the yokes and adapted to climb up reinforcing rods while lifting the mould, a working platform consisting of a rigid frame system covered by a floor, said working platform being freely and articulately sustained from said yokes by means of carrying pins protruding from said yokes, and provided with a plurality of brackets reaching beyond its edges in register with the pins of the yokes, those of the brackets registering with said lifters having a notch cut therein from below, the faces of said notches straddling corresponding pins, which latter thus provide support for the entire platform.
2. A concrete casting apparatus, comprising inner and outer walls forming a sliding mould, said walls being connected and spaced apart by a plurality of yokes for lifting the mould, lifters rigidly connected with some of the yokes and adapted to climb up reinforcing rods while lifting the mould, a working platform consisting of a rigid frame system covered by a floor, said working platform being freely sustained from said yokes by means of carrying pins protruding from said yokes and provided with a plurality of brackets reaching beyond its edges in register with the pins of the yokes, those of the brackets registering with said lifters having a notch cut therein from below, the faces of said notches straddling corresponding pins, which latter thus provide support for the entire platform.
3. A concrete casting apparatus, comprising inner and outer walls forming a sliding mould, said walls being connected and spaced apart by a plurality of yokes for lifting the mould, lifters rigidly connected with some of the yokes and adapted to climb up reinforcing rods while lifting the mould, a working platform consisting of a rigid frame system covered by a floor, said working platform being freely sustained from said yokes by means of carrying pins protruding from said yokes and provided with a plurality of brackets reaching beyond its edges in register with the pins of the yokes, those of the brackets registering with those of the yokes having no lifters, being provided with a notch in their top surface, lastmentioned notches gripping with their faces corresponding pins from below, in order to assist in lifting the mould by distributing lifting forces transferred through the platform to those yokes having no lifter, thereby promoting a most uniform lifting of the entire mould.
4. An apparatus for casting houses, silos and the like, comprising inner and outer walls forming a sliding mould, said walls being connected and spaced apart by a plurality of yokes for lifting the mould, lifters rigidly connected with some of the yokes and adapted to climb up reinforcing rods while lifting the mould, a working platform constituted by a rigid frame system covered by a floor and further of a post located centrally of the mould below said platform, a spider of braces connecting the base of the post with the edges of the platform, said working platform being freely sustained from said yokes by means of carrying pins protruding from said yokes and provided with a plurality of brackets reaching beyond its edges in register with the pins of the yokes, those of the brackets registering with said lifters having a notch cut therein from below, the faces of said notches straddling corresponding pins, which latter thus provide support for the entire platform, the rest of the brackets registering with those of the yokes having no lifters, being provided with a notch in their top surface, lastmentioned notches gripping with their faces

corresponding pins from below, in order to assist in lifting the mould by distributing lifting forces transferred through the platform to those yokes having no lifter, thereby promoting a most uniform lifting of the entire mould.

4. An apparatus for casting concrete buildings and silos comprising inner and outer walls forming a sliding mould, both walls being built up of a number of rigid sections bolted together into loose engagement so as to permit a limited relative motion therebetween, said walls being connected and spaced apart by a plurality of yokes for lifting the mould, lifters rigidly connected with some of the yokes and adapted to climb up reinforcing rods while lifting the mould, a working platform consisting of a rigid frame system covered by a floor, said working platform being freely sustained from said yokes by means of carrying pins protruding from said yokes and provided with a plurality of brackets reaching 20 beyond its edges in register with the pins of the yokes, those of the brackets registering with said lifters having a notch cut therein from below, the faces of said notches straddling corresponding pins, which latter thus provide support for the 25 entire platform, the rest of the brackets, regis-

tering with those of the yokes having no lifters, being provided with a notch in their top surface, last mentioned notches gripping with their faces corresponding pins from below, in order to assist in lifting the mould by distributing lifting forces transferred through the platform to those yokes having no lifter, thereby promoting a most uniform lifting of the entire mould.
